UNITED STATES PATENT OFFICE

WILLIAM W. WOODROOF AND CHARLES T. WOODROOF, OF WILKINSBURG,
PENNSYLVANIA

DESIGN FOR A TEETOTUM

Application filed October 10, 1930. Serial No. 37,222. Term of patent 3½ years.

To all whom it may concern:

Be it known that we, WILLIAM W. WOODROOF and CHARLES T. WOODROOF, both citizens of the United States, residing at Wilkinsburg, in the county of Allegheny and State of Pennsylvania, have invented a new, original, and ornamental Design for Teetotums, of which the following is a specification, reference being had to the accompanying drawings, forming part thereof.

Fig. 1 is a perspective view of the teetotum.

Fig. 2 is a longitudinal section taken substantially through the center of the teetotum.

Fig. 3 is a cross-section taken through the body-portion of the teetotum, on line 3—3.

Fig. 4 is a cross-section taken substantially on line 4—4 through the handle of the teetotum.

As shown in the drawings, our teetotum design comprises a body portion 1 of polygonal shape, having a semi-spherical extension 2 terminating with a spherical ball 3 upon which the teetotum is spun and simulating a golf-ball.

The handle 4 of the teetotum consists of a plurality of iron-headed golf-club-imitations grouped together as shown.

We claim:

The ornamental design for a teetotum, as shown and described.

In testimony whereof we affix our signatures.

WILLIAM W. WOODROOF.
CHARLES T. WOODROOF.
